UNITED STATES PATENT OFFICE.

JAMES LOMAS TONGE, OF APPONAUG, RHODE ISLAND.

SHORT-CIRCUITING MECHANISM.

1,327,259.

Specification of Letters Patent.

Patented Jan. 6, 1920.

Application filed February 18, 1919. Serial No. 277,713.

To all whom it may concern:

Be it known that I, JAMES L. TONGE, a citizen of the United States, and resident of Apponaug, in the county of Kent and State of Rhode Island, have invented certain new and useful Improvements in Short-Circuiting Mechanism, of which the following is a specification.

This invention relates to a key-operated mechanism for short circuiting an electric current, and the object of this invention is to provide a simple, inexpensive and effective means whereby the electric current in an internal combustion engine may be readily short circuited so as to render the engine inoperative.

With these and other objects in view, the invention consists of certain novel features of construction, as will be more fully described, and particularly pointed out in the appended claims.

In the accompanying drawings:

Figure 1— is a sectional side elevation of my improved short-circuiting mechanism.

Fig. 2— is a front view of the device partly broken away to illustrate the connection of the binding post with the conductor member.

Fig. 3— is a sectional view looking from the rear of the device, showing the sliding contact plate which is moved by the key to complete the short circuiting path.

Fig. 4— is a sectional side elevation showing my improved device in operating position on the vehicle.

Referring to the drawings, 10 indicates the engine of a motor vehicle and 11 the transmission housing within which is set the magneto or electric current generator 40 of which the member 12 is fixed while the member 13 is rotated through the action of the fly wheel 14, all of which is mounted beneath the foot board 15 or body portion of the vehicle.

My improved short-circuiting device may be constructed in any suitable way, but I preferably construct the same with a hollow or tubular standard or casing 16 which is preferably formed of conducting material such as cast brass, iron, or the like, the head 17 of which is enlarged and bored at 18 for the reception of the lock or key actuated mechanism 19.

Within this tubular standard I have mounted a rod 20 of conducting material

which is insulated from the standard proper by a surrounding core 21. This insulating core performs three functions; first, it insulates the rod from the standard; second, it supports the rod centrally with the standard; and third, it stiffens the standard so that its thin, tubular walls can withstand a greater shock without becoming broken.

At 22 this conductor member is slightly enlarged and into the enlarged portion is threaded a binding post 23 which extends out through the insulating collar 24 and is threaded at its outer end for the nut with which to secure the circuit wire 25 which extends up to the ignition coil 38.

On the lower end of this conductor rod 20 is a coil spring 26 which serves as a yieldable electrical connection between this conductor and the contact pin 27, which pin is designed to rest upon the fixed plate 28 of the magneto or generator.

The upper end of this conductor rod 20 is also provided with another yielding pin 29 mounted in a recess therein and is pressed outwardly by means of the spring 30 also mounted in the recess in the rod. The upper edge 31 of this recessed portion is turned inwardly forming a shoulder to limit the outward motion of this contact pin 29.

The key actuated locking mechanism is provided with a sliding plate 40 which is arranged to move vertically in the groove 32 and is provided with a rearwardly extending operating pin 33. The rotating member 34 of the lock is provided with an operating pin 35 whereby when this member is rotated in one direction the pin 34 contacts with pin 33 and moves this plate downwardly so that its end 36 engages the yielding pin 29 to complete the short circuiting path back to the engine casing, through this plate, the rest of the key-actuated mechanism, through the standard 16 and the attaching screws or bolts 37.

In order to open this short-circuiting path and restore the effectiveness of the normal circuit, it is only necessary to turn the key in the opposite direction, which will cause the pin 35 to be moved around beneath the pin 33 and so raise the sliding plate 31 out of contact with the yielding contact pin 29.

In some makes of motor vehicles the yielding contact pin 27 is mounted in a suitable support (not shown) and forms a part of the standard equipment to which is con-

nected a conductor wire leading up to the ignition coil 38.

My device is designed to take the place of this support and mount this contact pin at the lower end of a long standard 16, which extends up inside of the dash 39 beneath the ignition coil within easy reach of the driver, this contact pin 27 being in circuit with the ignition coil through the conductor 10 rod 20 and the wire 25. This device may be readily applied to any car of this type practically without alteration to the car.

My improved short-circuiting device is extremely simple in construction, easy to install, and is very effective in its operation as when the key has thrown the mechanism to short-circuit the flow of current, it is quite impossible to start the engine.

I have shown and described a structure 20 whereby the standard itself is formed of a conducting material and is used as a return path for short-circuiting the current, but I do not wish to be restricted to this particular construction and arrangement of parts as 25 other short-circuiting paths may be provided and controlled by the operation of key-actuated mechanism.

The foregoing description is directed solely toward the construction illustrated, but I 30 desire it to be understood that I reserve the privilege of resorting to all the mechanical changes to which the device is susceptible, the invention being defined and limited only by the terms of the appended claims.

35 I claim:

1. A device of the character described comprising a tubular metal standard having a suitable attaching base, a conductor mem-

ber in said standard and interposed into the electric circuit, insulating material for positively supporting said conductor within said standard, a yieldable member on said conductor in contact with the source of electric energy, a binding post supported on the outside wall of said standard insulated therefrom and connected to said conductor and to which binding post the normal circuit wire may be connected, and key-actuated mechanism adapted to be moved to contact with said conductor to short circuit the current through said standard. 40 45

2. A device of the character described comprising a tubular metal standard having a suitable attaching base, a conductor member in said standard and interposed into the electric circuit, insulating material for positively supporting said conductor within said standard, a yieldable member on said conductor in contact with the source of electric energy, a binding post supported on the outside wall of said standard insulated therefrom and connected to said conductor and to which binding post the normal circuit wire may be connected, a key-actuated U-shaped sliding plate having a projection adapted to engage the upper end of said conductor, and means whereby the operating of said plate makes a yielding contact with said conductor to short circuit the current through said standard. 50 55 60 65 70

In testimony whereof I affix my signature in presence of two witnesses.

JAMES LOMAS TONGE.
